2 SHEETS-SHEET 2.

UNITED STATES PATENT OFFICE.

CARL L. GROHMAN AND IRA C. KOEHNE, OF DAYTON, OHIO, ASSIGNEES TO THE NATIONAL CASH REGISTER COMPANY, OF DAYTON, OHIO, A CORPORATION OF OHIO, (INCORPORATED IN 1906.)

CHECK CASH-REGISTER.

1,014,647.

Specification of Letters Patent.

Patented Jan. 16, 1912.

Application filed December 3, 1906. Serial No. 346,070.

To all whom it may concern:

Be it known that we, CARL L. GROHMAN and IRA C. KOEHNE, citizens of the United States, residing at Dayton, in the county of 5 Montgomery and State of Ohio, have invented certain new and useful Improvements in Check Cash-Registers, of which we declare the following to be a full, clear, and exact description.

10 This invention relates to cash registers and has among its objects to provide a check or coin display serving to retain on exhibition the checks or cash received during several operations of the machine.

15 A further object is to provide an improved check or coin conveying mechanism whereby the check or coin deposited may be moved gradually past a sight opening and finally deposited in the machine.

20 Another object is to provide a check or coin display connected to a cash register of an ordinary type so that the operation of the cash register may serve if desired to actuate the check display and that the operation of the check display may in turn if desired actuate the cash register.

With these and incidental objects in view the invention consists in certain novel features of construction and combination of 30 parts, the essential elements of which are set forth in appended claims and a preferred form of embodiment of which is hereinafter described with reference to the drawings which accompany and form part of this 35 specification.

Of said drawings: Figure 1 is a vertical transverse section through a well known type of cash register to which our invention may be applied, this view showing only a 40 few parts of the register. Fig. 2 is a transverse vertical section through the check displaying mechanism.

The invention is shown as applied to a cash register of the type patented to Thomas 45 Carney No. 532,762, Jan. 22, '95, but it will be understood that this is merely by way of illustration and the check display may be used with many other types of register. For a full description of the cash register reference may be made to the above patent but 50 it may be generally stated that the register is provided with a series of value keys 10 and special keys 11 all journaled loosely on a main rod 12 and each provided at the

rear end with a projection 13 on which rest 55 indicator standards 14 for each key. The standards 14 have tablets 15 mounted thereon and are raised to bring the tablets 15 into indicating position. A key coupler 16 is mounted on trunnions 17 in the main 60 frame of the machine, a rear extension 18 of said coupler serving to pass into notches 19 of the amount and special keys thereby compelling the keys to move together. The amount keys 10 are normally directly abutting 65 the coupler while the special keys 11 have a cut away portion 20 under the coupler so that the key may be raised slightly without moving the coupler. To prevent return of the special keys when so raised 70 a latch pawl 21 is provided on each special key, the depending end of said pawl being adapted to engage the portion 22 of the machine frame when the special key 11 has been slightly raised. When the special key 75 has been so raised a spring 23 serves to move the depending end of the pawl 21 rearwardly enough to engage the frame standard 22. As the special keys 11 have some movement before the key coupler is encountered 80 it is necessary to provide some means for returning the said keys with the coupler and to this end is pivoted on each special key 11 as indicated at 24 a pawl 25 having a projection 26. When the special key 11 85 and amount key 10 are operated the coupler rises with the two keys and the rear extension 18 thereof gradually enters the notches 19 of both keys. This relative rearward movement of the coupler serves to rock the 90 pawl 25 around its pivot 24 finally carrying the projection 26 under a hook 27 of the pawl 21 when the spring 23 immediately passes the hook 27 over the projection 26 thereby latching the pawl 25 so that it projects directly under the key coupler extension 18. As the coupler moves down it will be evident that the special key 11 will be forced down through the agency of the pawl 25 which is still held locked by the hook 27. 100 When the keys reach nearly their lowest position the beveled edge 28 of the pawl 21 strikes the frame piece 22 forcing the pawl 21 against the tension of its spring 23 and thereby withdrawing the hook 27 from the 105 projection 26 of the pawl 25, so that the pawl 25 may assume its normal position shown in Fig. 1.

The mechanism as thus far described is found in the machine as now on the market and is not part of the present invention. This invention is comprised in the check display shown in Fig. 2 and may now be described.

It was previously stated that the key coupler 16 was mounted on trunnions 17 journaled in the main frame of the machine. 10 One of these trunnions 17 is extended and on the outer end thereof is rigidly fastened a depending arm 31 having a notch 32 cut in the bottom thereof. Riding in this notch is a tooth 33 of a bell crank arm 34 journaled 15 on a pin 35^a which is mounted on an arm 36 loose on the trunnion 17 of the key coupler. It may be here noted that Fig. 2 is drawn from the opposite side to that from which Fig. 1 is drawn so that a counter 20 clockwise motion of the coupler as viewed in Fig. 1 will produce a clockwise motion of the arm 31 as viewed in Fig. 2. The bell crank 34 is provided at the rearward end with a flange 35 normally in front of a locking block 36^a. When the amount key 10 is 25 slightly operated as is the case in the type of machine shown, the coupler is raised slightly and arm 31 is therefore thrown rearwardly rocking bell crank 34 around its pivot 35^a 30 and depressing flange 35 below the lug 36^a and below a locking notch 37 of a locking arm 38 also journaled loosely on the coupler trunnion 17. This arm 38 carries a pin 39 35 on which is loosely mounted an arm 40 normally drawn by a spring 41 connecting a pin 42 on the said arm to a pin 43 on arm 36. It will be clear that when bell crank 34 is rocked as above stated and flange 35 thereof depressed that the locking notch 37 40 of arm 38 will move over the flange 35 under the impulse of spring 41 and retain the said flange and the attached mechanism in the adjusted position. A bar 51 is provided 45 riding on an antifriction roller 52 at its rearward end and at its forward end is bifurcated to form racks 53 and 54 meshing 50 successively with a gear 55. The bar 36 has mounted thereon a pin 56 carrying an antifriction roller 57, the said roller passing through a slot 58 in arm 31 and a slot 59 in bar 51. It will be seen from the shape 55 of the slot 58 that the described motion of the arm 31 may take place without moving the roller 57 or its carrying bar 36, the purpose of which is to rock the flange 35 out of the path of the locking lug 36^a so as to enable the rocking of bar 36 when the forward end of the slot 58 in arm 31 contacts with the pin 56 projecting from said bar. 60 By this means the handle 95^a, as hereinafter described, is locked from operation until the coupler 16 has been partly moved. When however the key 10 is given its complete operative stroke the arm 31 is moved farther 65 rearward and by reason of the forward end

of the slot 58 contacting with the roller 57 will move the bar 36 carrying said roller rearward and through the roller 57 and slot 58 moves the bar 51 also rearward. At this time the flange 35 rides along the under side of locking lug 36^a carrying with it also the arm 38 and arm 40 mounted thereon. This arm 40 rides along the top of the lug 36^a as it is provided with a flange 62 which when the arm 40 is slightly depressed strikes the top of the said lug 36^a. Before the key 10 completes its movement to raise the key coupler the flange 62 passes over the rearward end of the lug 36 and then moves downwardly. When the keys of the register return to normal position the arm 31 moves forwardly carrying the flange 35 forward under the locking lug 36^a, but during this motion the flange 62 strikes the rear edge of lug 36^a and is held there, thereby 80 stopping the motion of arm 38 which has previously moved with the flange 35. Further movement of arm 31 carries flange 35 away from the locking notch 37 of the arm 38 and said flange finally passes free of the locking lug 36^a when it rises to the position shown in Fig. 2. It was stated that during this operation the flange 62 remained against the rear edge of the locking lug 36^a and it will be clear that the upward movement of 95 flange 35 will rock the arm 40 around its pivot at 39 thereby carrying the flange 62 above the lug 36^a. When this happens the spring 41 will draw the arms 38 and 40 forwardly returning them to the position shown 100 in this figure.

It was stated that racks 53 and 54 mesh successively with a gear 55. This gear is fast to a roller 71 around which is fastened a conveying belt 72 having a number of 105 cleats 73 spaced around the same at equal distances. At the rear end the conveying belt passes around the roller 74 journaled in the main frame. On the rod 75 carrying the gear 55 and the attached mechanism is journaled an arm 76 normally urged to rotate to the right by a spring 77 connecting one end of said arm to the main frame. Rollers 78 and 79 are provided on racks 53 and 54 and these rollers are adapted to engage and 115 rock the arm 76 to tension its spring 77. Attached to the bar 51 is a projection 82 having a flange 83 beveled as shown. On the frame of the machine is a second similarly beveled lug 84 adapted to coöperate with the lug 83. The purpose of these two lugs and the arm 76 is to insure that the reciprocation of the bar 51 will produce a continued rotation of gear 55 and therefore a continued 120 forward movement of the conveying belt. 125

Fig. 2 shows the parts in normal position and it will be remembered that an operation comprises a movement of arm 31 toward the left of the figure and then a reverse movement thereof. When arm 31 is so 130

5 moved toward the left the forward edge of slot 58 will soon abut the antifriction roller 57 and the further movement of arm 31 will carry the roller 57 and bar 51 rearwardly.
 10 The rack 53 is now in mesh with the gear 55, a counter clockwise movement of the said gear is produced, and at the same time roller 78 engages the rear end of arm 76 and gradually rocks the same against the tension of spring 77. Meanwhile camming lug 83 is moved under camming lug 84, and finally passes free of the rearward end of the same. When this occurs the spring 77 may contract, rocking the arm 76 and therefore 15 through the antifriction roller 78 raising the bar 51 at the forward end thereof. This bar is raised enough to carry the rack 54 into mesh with gear 55 and arm 31 then moves back to its normal position carrying 20 the bar 51 with it. During this return movement of bar 51 the beveled lug 83 rides over lug 84 and the antifriction roller 79 finally engages and rocks arm 76 again tensioning spring 77. At the end of the forward stroke 25 of bar 51 the lug 83 passes free of lug 84 and it and the bar 51 are immediately depressed by spring 77. This operation takes place at each actuation of the device and clearly serves to give the conveying belt 72 a forward motion twice at each operation. The extent of movement is arranged to be just sufficient to place a succeeding cleat 73 30 in the previous position of the preceding cleats so that at the end of any operation 35 the cleats as a whole occupy precisely the same position.

40 Directly over the conveying belt is a piece of transparent material 92 through which the checks or money on the belt may be observed. The inserted articles are deposited through the cut away portion 93 of the display frame and allowed to drop on a table 94 having corrugations 95 on the top thereof. A frame comprising pivoted arms 45 94^a connected by a rod 95^a is journaled on a main rod 96 and is connected through a link 97 with the arm 36. Depending from the handle rod 95^a is a frame including a bar 48 having depressions complementary to 50 the corrugations 95. It will be remembered that antifriction roller 57 mounted on arm 36 passes into the slot 59 of bar 51 and thereby compels the said arm to move rearwardly at each operation of the machine in correspondence with the movement of bar 51. 55 This mechanism clearly provides that the frame bar 98 will be swung over the corrugations 95 of the table 94 and will serve to push any articles deposited on said table before it and finally allow them to drop on 60 the conveying belt 72. When the frame rod 98 reaches the rearward limit of its travel to deposit the inserted articles on the belt the cleat 73 indicated by 73^x is directly abutting 65 the rear end of table 94 thereby preventing

the coins from dropping off of the conveying belt. As the mechanism is returned to normal position the cleat 73^x finally reaches the position shown in the figure as occupied by the preceding cleat and it will be clear 70 that in this position of the mechanism a withdrawal of the inserted articles is not possible, since a belt guard 73^y attached at opposite ends of the main frame holds the belt and its cleats 73 so close to the transparent material as to preclude their withdrawal through any crevice. Depending rigidly from the rear edge of said table 94 is an arc-shaped sheet of metal 94^x compelling the displaying as aforesaid of articles which 80 otherwise might be thrown over the rear edge of table 94 and downward into the drawer.

85 The mechanism has been described as if all the power was furnished by the register keys the display handle serving as a mere pushing device for the inserted articles. It will be observed however that the whole operation may take place by the manual moving rearward of the handle bar 95^a, 90 which will, through link 97, rock the arm 36 just as it was rocked by the complete operation of the key. It is of course necessary in this scheme of operation to slightly depress the amount key 10 to move the flange 35 95 from in front of the locking lug 36^a but when this is done the slightly operated key 10 is attached to the key coupler 16 and the further movement of said coupler through the handle rod 95^a and the connecting 100 mechanism will serve to completely operate the register key.

105 The display is provided with a cash safe having a movable part which is released by the operation of the value keys. This cash safe is shown in the present case and it will be understood that it is in the base of the display and is to be ejected when desired. A lateral flange is provided on the forward end of this drawer and this engages 110 a latch 121 pivoted on a pin 122 and adapted when the drawer moves outwardly to a very slight extent only to drop over the pin 123 connecting the link 97 to the arm 94^a. This mechanism clearly serves to lock the display if the cash drawer is out of normal position. When the cash drawer is pushed completely in the flange referred to strikes the lower end of latch 121 raising the hook 115 end of the same away from pin 123 so that the display may again be operated.

120 As the conveyer belt is moved intermittently at succeeding operations the inserted articles are gradually brought to the rear thereof and finally pass over the roller 74 dropping into a receptacle 126 from which they may be taken at any desired time and in any desired manner.

125 As previously described, the partial operation of any of the keys 10 will with- 130

draw the flange 35 of the bell crank 34 out of the path of the locking lug 36^a, thereby permitting the operation of the handle 95^a by the operator in connection with the key 10 so as to assist said key in the operation of the machine. This conjoint operation of the key 10 and the handle 95^a prevents any torsional strain of the parts that might occur if either the key or handle were operated 10 alone.

It will be seen that the register keys comprise a primary driving mechanism for the conveying belt and the hand lever mechanism and parts connected thereto form a supplementary driving means for the same. A locking means for the supplementary driving means is found in the bell crank 34 and attached parts, this locking means being actuated by the primary driving means. This 15 mechanism is of use in many other relations besides that indicated in the drawings and it is desired to claim it without reference to the particular function performed in this case and without reference to the particular 20 mechanism employed to perform the said function. The arched detent 38 provides a second locking means which is released by the arm 40 pivoted thereto, this arm 40 serving to hold the locking means previously 25 referred to in its unlocking position. This mechanism is also of use in other relations besides that in which it is shown.

While the form of mechanism here shown and described is admirably adapted to fulfil 30 the objects primarily stated, it is to be understood that it is not intended to confine the invention to the one form of embodiment herein disclosed, for it is susceptible of embodiment in various forms all coming within 35 the scope of the claims which follow.

What is claimed is as follows.

1. In check mechanism, the combination with a check carrying means, of devices for moving said means, a latch for said devices, 40 and a key and connections for first actuating said latch and then operating said devices.

2. In check mechanism, the combination with a check carrying means, of a rack and connections for moving same, means for 45 latching said connections, and a manipulative device and connections for withdrawing said latching means and then operating said rack and connections.

3. In check mechanism, the combination with a check conveying means, of mechanism for moving said means, latching devices for said mechanism, a manipulative device and connections and a handle and connections to first release said latching means 50 and then actuate the moving mechanism.

4. In a check mechanism, the combination with a conveying means for checks, of mechanism for actuating said conveying means, a latching device for said mechanism, a 55 manipulative device for releasing said latch-

ing device and operating said actuating mechanism and means for retaining said latching device in releasing position.

5. In check mechanism, the combination with a conveying means for checks, of means 70 for operating same, latching devices for said operating means, a key having connections whereby its initial movement operates said latching devices, and a handle for actuating said operating means and said key.

6. In check mechanism, the combination with a driven mechanism, of a driving mechanism for same, means normally latching said driven mechanism, a device for releasing said latching means, an arm for 80 holding said latching means in releasing position, and means for tripping said arm.

7. In check mechanism, the combination with a conveyer belt for carrying checks, of a gear for driving same, a rack and connections for operating said gear, means for 85 normally preventing movement of said rack, and a key for releasing said last named means and then operating the rack.

8. In check mechanism, the combination with a conveying means for checks, of a rack bar for driving same, an actuating device for said rack bar, latching means mounted on said actuating device, and a key and a member coupled thereto by the movement of 90 said key for first actuating said latching means and then operating said actuating device.

9. In check mechanism, the combination with a conveyer for checks, of double racks 100 for moving same, an actuating device for said racks, means for latching said actuating device, a key and connections for releasing said latching means and then operating said actuating device and racks, and a handle for also operating said actuating device and racks.

10. In check mechanism, the combination with a driven mechanism, of a primary driving device therefor, a supplemental 110 driving device for said driven mechanism, and latching means for said supplemental driving device arranged to be operated to release same by said primary driving device.

11. In check mechanism, the combination with check carrying means, of a primary driving mechanism therefor including a key, a supplemental driving mechanism for said check carrying mechanism and a locking means for said supplemental mechanism operated by said primary mechanism.

12. In check mechanism, the combination with a driven mechanism, of primary and supplemental driving means therefor, a lock for said supplemental means operated by 125 the initial movement of said driving means, and a latch for holding said lock in releasing position.

13. In check mechanism, the combination with a driven mechanism, of primary and 130

supplemental driving means for same, means normally locking said supplemental means and arranged to be released by said primary means, and a latching device for holding said locking means in releasing position, the return of said primary means to normal position serving to replace the locking means and latching devices.

14. In check mechanism, the combination with a check conveying mechanism, of a gear for driving same, a bar having two opposite racks for separately engaging said gear, means for retaining the racks in engagement with the gear during movement in opposite directions, means for shifting the rack bar at the end of movement in each direction to cause engagement of the idle rack, and manipulative means and connections for operating said rack bar.

15. In a machine of the class described, the combination with a stationary platform, of a conveyer to which articles are transferred from the stationary platform, means for transferring articles from the platform to the conveyer, and means for actuating the conveyer and the transferring means, the latter being constructed so as to assist in the operation of the actuating means.

16. In a machine of the class described, the combination with a stationary platform upon which articles are deposited, of a conveyer to which articles are transferred from the stationary platform, a normally locked means for transferring articles from the platform to the conveyer, and means for first unlocking the transferring means and then actuating it.

17. In a machine of the class described, the combination with a stationary platform upon which articles are deposited, of a conveyer to which articles are transferred from the stationary platform, a normally locked means for transferring articles from the platform to the conveyer, and means for first unlocking the transferring means and then actuating it, the transferring means being constructed so as to assist in the operation of the actuating means.

18. In a machine of the class described, the combination with a check carrying

means, of a primary and a supplemental driving means therefor, means for normally disabling the supplemental driving means, and means controlled by the primary driving means for enabling the supplemental driving means.

19. In a machine of the class described, the combination with a check carrying means, of a primary and a supplemental driving means therefor, means for normally locking the supplemental driving means, and means controlled by the primary driving means for unlocking the supplemental driving means.

20. In a machine of the class described, the combination with a check carrying means, of a primary and a supplemental driving means therefor, means for normally locking the supplemental driving means, means controlled by the primary driving means for unlocking the supplemental driving means, and means for holding the locking means in an inoperative position until near the end of operation of the primary driving means.

21. In a machine of the class described, the combination with a check carrying means, of a key and connections for actuating said carrying means, a lever and connections for also actuating said carrying means, means for normally locking the lever and connections, and means actuated by the key and connections for unlocking the lever and connections.

22. In a machine of the class described, the combination with a driven member, of a primary and a supplemental driving means therefor, means for normally locking the latter, and means controlled by the primary driving means for unlocking the supplemental driving means so as to enable the latter to assist in driving the driven member.

In testimony whereof we affix our signatures in the presence of two witnesses.
